THREAD-CONTROLLING MECHANISM FOR
SEWING MACHINES

Rudolph Becker, North Plainfield, N. J., assignor
to The Singer Manufacturing Company, Elizabeth, N. J., a corporation of New Jersey

Application March 5, 1946, Serial No. 652,081

11 Claims. (Cl. 112—242)

1.

This invention relates to chain-stitch sewing machines, and more particularly to a thread-controlling mechanism for a thread-carrying looper having loop-seizing and -shedding movements.

The invention has for an object to provide a simplified and efficient mechanism for controlling the thread, supplied to the looper of a chain-stitch sewing machine, with a degree of nicety such as to permit operation of the machine at high speed and to prevent snarling, whipping and knotting of the looper-thread during such operation.

Another object of the invention is to provide an improved thread-controller which is timed to draw thread from the supply and subsequently to assist in controlling the looper-thread to the extent that the limb of the looper-thread-loop which is seized by the spreader, as the same is actuated to open the usual thread-triangle, is held by the spreader until the needle on its next work-penetrating stroke has entered the thread-triangle.

With the above and other objects in view, as will hereinafter appear, the invention comprises the devices, combinations, and arrangements of parts, hereinafter set forth and illustrated in the accompanying drawings of a preferred embodiment of the invention, from which the several features of the invention and the advantages attained thereby will be readily understood by those skilled in the art.

In the accompanying drawings:

Fig. 1 is a front elevation, partly in section, of the head end of a chain-stitch sewing machine embodying the present invention.

Fig. 2 is a left hand end elevational view of the sewing machine, with the bed-portion in section, showing the path of travel of the looper-thread.

Fig. 3 is an enlarged plan view of a portion of the machine bed and the parts carried thereby, with certain cover plates and portions of the mechanisms omitted.

Fig. 4 is an enlarged sectional view taken substantially on the line 4—4, Fig. 3.

Fig. 5 represents an enlarged transverse vertical sectional view taken substantially at the line of feed, with a development of the orbital path of movement of the thread-controlling eye in the looper-shank.

Referring more particularly to the drawings, the invention is disclosed as embodied in a sewing machine having a frame comprising a box-like bed 10 from one end of which rises the usual standard (not shown) of an overhanging bracket

2.

arm 11 terminating in a head 12. Suitably journaled in the bracket-arm 11 is a main or arm-shaft 13 adapted to be connected at the standard-end thereof by any suitable means to a bed-shaft 14 which is driven at the same speed as the arm-shaft 13.

Journalized for endwise reciprocation in the machine-head 12 are a pair of needle-bars 15 which are actuated by means preferably comprising a crank 16 integral with the arm-shaft 13 within the head 12. Embracing the crank 16 (Fig. 2) is the upper end of a pitman 17 connected at its lower end intermediate the ends of a vibratory lever 18 pivoted at its rear end on a fulcrum-stud 19 carried by the head 12. At its forward end the vibratory lever 18 is connected to the needle-bars 15 by a pair of links 20. Secured to the lower end of each of the needle-bars 15 is a block 21 having extending therethrough two horizontally disposed rods 22 upon which are secured for lateral adjustment a plurality of needle-clamps 23. Each of the needle-clamps 23 carries an eye-pointed thread-carrying needle 24. The needles 24 are adapted to penetrate work W which is held upon the usual throat-plate 25 of the bed 10 by the presser-feet 26 carried on the regular spring depressed presser-bars 27 endwise slideable in the machine-head 12.

30. The work W is adapted to be fed past the needles 24 by any suitable feeding mechanism including a serrated feed-dog 28 operable through conventional feed-dog slots 29 formed in the throat-plate 25. The connections illustrated in the drawings for imparting work-advancing movements to the feed-dog 28 are the same as those disclosed in my U. S. Patent No. 2,409,242, dated Oct. 15, 1946; and, therefore, no further reference thereto is deemed necessary in this case.

40. Cooperating with each needle 24 in the formation of two-thread chain-stitches is a thread-carrying looper 30 having a blade 31 terminating in a loop-seizing beak 32. Depending from the looper 30 is a cylindrical shank 33 adapted to extend through a bore 34 in a looper-carrier 35 and to be held therein by a set-screw 36. The mechanism illustrated in the drawings to impart loop-seizing and -shedding movements to the loopers 30 is the same as that disclosed in my U. S. patent application Serial No. 631,302, filed November 28, 1945, and only such reference will be made hereinafter to said mechanism as will give a full understanding of the present invention.

The looper-carrier 35 is adjustably secured to the proximate ends of aligned looper-driving shafts 37 and 38; the looper-carrier and the aligned looper-driving shafts forming, in effect, a single composite looper-carrying and -actuating shaft. In order that the composite looper shaft 35, 37 and 38 may be operated smoothly and without any binding or cramping action, means is provided for actuating the shaft synchronously from each end thereof. Accordingly, the looper shaft sections 37 and 38 are journaled, respectively, in eccentrically located bores 39 and 40 formed in sleeves 41 and 42 carrying eccentric gears 43 and 44. The sleeves 41 and 42 are journaled in bearing bushings 45 and 46 in the base 10 of the machine.

Secured eccentrically upon the bed-shaft 14 (Fig. 3) are two looper-driving gears 47 and 48 complementary to and meshing, respectively, with the gears 43 and 44 on the sleeves 41 and 42. Thus rotation of the bed-shaft 14 effects, through the eccentric gears 43-47 and 44-48, rotation at a varying rate of the sleeves 41 and 42 in their bearing bushings 45 and 46, thereby moving the looper-carrier 35 laterally of its axis in an orbit.

During the variable speed travel of the looper-carrier 35 in its orbit, said looper-carrier is also oscillated on its own axis. This oscillation is effected by the mechanism clearly shown in Fig. 4, and comprises preferably an eccentric or crank 49 formed on the bed-shaft 14. The crank 49 is embraced by a split-block 50 having in its lower portion a cylindrical bore 51. Slidably fitted within the bore 51 is a lever-pin 52 having a split head 53 secured by screws 54 and 55 upon the portion 38 of the looper-actuating shaft. From the above description, it will be understood that the looper-carrier 35 is caused to move in an orbital path by the rotation of the aligned sleeves 41 and 42 and that simultaneously with this movement the looper-carrier is caused to oscillate about the axis of the aligned shaft sections 37 and 38 by the pin-and-sleeve connection 50-52. The path traversed by the looper 30 resulting from this compound movement of the looper-carrier 35 is fully disclosed in my above mentioned U. S. patent application Serial No. 631,302.

As is common in chain-stitch machines, each looper 30 has cooperating therewith, in forming the usual thread-triangle for entrance by the descending needle, a spreader-finger 56. These spreader-fingers are secured to a horizontally disposed member 57 mounted to slide in a channel 58 provided in the under side of the throat-plate 25. At one end the member 57 is connected to a slide-bar 59 (Fig. 1) slidably mounted within a guide-way 60 formed in the under side of a block 61 secured to the bed 10 of the machine. The slide-bar 59 carries a roller-stud 62 which tracks a cam-groove 63 formed in a barrel-cam 64 suitably secured to a side face of the gear 43.

It will be observed in Fig. 2 that the spreader-finger 56 is adapted to seize the limb of the looper-thread L leading from the eye in the looper-beak 32 to the last stitch in the work. After this thread-limb is seized, the spreader-finger 56 continues in its movement to distend said thread-limb, thereby effectively to enlarge and properly position the thread triangle, of which the seized thread-limb is a part, for entrance by the descending needle 24. In order to insure the seizure of the thread-limb by the spreader-finger 56, it is necessary to control the looper-thread to the ex-

tent that the thread-leading from the eye in the looper-beak 32 to the work is substantially straight and intersects the path of travel of the spreader-finger. Moreover, after seizure of the looper-thread by the spreader-finger, it is essential that the looper-thread be controlled so that the seized thread-limb be retained on the spreader-finger at least until the needle has entered the formed thread-triangle.

Novel means is provided for drawing a length of thread from the supply and for obtaining the above described thread control. This means is best illustrated in Figs. 2 and 5. It will be seen that the cylindrical shank 33 of the looper 30 has been extended below the looper-carrier 35, and adjacent its lower end is formed with a transverse thread-eye 65 which moves relative to and cooperates with fixed thread-guides 66 and 67. The thread-guide 66 is formed in an angle-bar 68 which is slotted, as at 69, to receive clamp-screws 70, whereby the angle-bar 68 can be vertically adjusted for a limited extent. The thread-guide 67 is formed in an angle-bar 71 secured by screws 72 to the bed 10. It will be appreciated that the movable thread-eye 65 is disposed on that side of the axis of movement of the carrier 35 opposite or remote from the looper-blade 31 and that the thread-eye will move in an orbital path somewhat like that of the looper-beak 32, but in the opposite direction. The exact path of movement of the thread-eye 65 during the stitch-forming cycle is designated as O in Fig. 5. The most desirable control of the looper-thread L is obtained by locating the fixed thread-guides 66 and 67 on opposite sides of the movable thread-eye 65, so that the thread-eye operates on the thread passing between the thread-guides. Also, it is desirable to locate the fixed thread-guides 66 and 67 reasonably close together so that the length of thread extending from the thread-guide 67 through the thread-eye 65 and to the thread-guide 66 will be short. This renders the action of the movable thread-engaging element or thread-eye 65 more accurate in its effect on the thread by minimizing stretching resulting from the inherent elasticity in the thread. It will also be seen that the orbital path of movement of the thread-eye 65 is located at one side of a straight line connecting the two thread-guides 66 and 67.

Having thus set forth the nature of the invention what I claim herein is:

1. A sewing machine having in combination, a reciprocating thread-carrying needle, a thread-carrying chain-stitch looper complementary to said needle in the formation of stitches, a carrier for said looper, means for moving said carrier about an axis to impart loop-seizing and loop-shedding movements to said looper, a pair of thread-guides, and a thread-engaging element carried by said carrier at one side of the axis of movement of said carrier and operable on the thread passing between said thread-guides.

2. A sewing machine having in combination, a reciprocating needle, a thread-carrying chain-stitch looper complementary to said needle in the formation of stitches, a carrier movable about an axis and supporting said looper at one side of said axis, means for actuating said carrier, a pair of thread-guides for directing the looper thread, and a thread-engaging element carried by said carrier on the side of the carrier-axis opposite to said looper for contacting the thread passing between said thread-guides.

3. A sewing machine having in combination, a reciprocating needle, a thread-carrying chain-

stitch looper having an eye-pointed beak complementary to said needle in the formation of stitches, a carrier supporting said looper, means for actuating said carrier about an axis in a manner to move said looper-beak in an orbital path, a pair of thread-guides for said looper-thread, and a thread-engaging element operable on the thread passing between said thread-guides, said thread-engaging element also traversing an orbital path and movable in a direction opposite to that of the looper-beak.

4. A sewing machine having in combination, a reciprocating needle, a thread-carrying chain-stitch looper having a beak complementary to said needle in the formation of stitches, a carrier supporting said looper and movable in an orbital path about an axis, means for moving said carrier, a pair of fixed thread-guides for said looper-thread, and a thread-engaging element carried by said carrier and spaced from the axis about which said carrier moves, whereby said thread-engaging element traverses an orbit between said fixed thread-guides.

5. A sewing machine having in combination, a reciprocating needle, a thread-carrying chain-stitch looper having a beak complementary to said needle in the formation of stitches, a pair of thread-guides, a carrier supporting said looper and movable in an orbital path about an axis disposed transversely of the plane containing said fixed thread-guides, and a thread-engaging element supported by said carrier and disposed to traverse an orbital path between said thread-guides.

6. A sewing machine having in combination, a reciprocating needle, a thread-carrying chain-stitch looper having a beak complementary to said needle in the formation of stitches, a carrier supporting said looper and movable in an orbital path about an axis, means for moving said carrier, a pair of fixed thread-guides for said looper-thread, and a thread-engaging element carried by said carrier and disposed so that said element moves in an orbital path to one side of a straight line connecting said thread guides.

7. A sewing machine having in combination, a reciprocating needle, a thread-carrying chain-stitch looper, a carrier supporting said looper and movable about an axis, means for actuating said carrier about said axis so that said looper moves in an orbit contained in a plane parallel to said needle, a pair of spaced thread-guides for directing said looper-thread, a movable thread-engaging element disposed to operate on the looper-thread between said thread-guides, and means to

move said thread-engaging element in an orbit similar to the orbit of movement of said looper.

5 8. A sewing machine having in combination, a reciprocating thread-carrying needle, a thread-carrying chain-stitch looper complementary to said needle in the formation of stitches, a carrier for said looper, means for moving said carrier about an axis to impart loop-seizing and loop-shedding movements to said looper, and a thread-controller for said looper-thread including spaced thread-guides, and a thread-eye carried by said looper and operable on the thread passing between said thread-guides.

15 9. A sewing machine having in combination, a reciprocating thread-carrying needle, a thread-carrying chain-stitch looper having a blade terminating in a loop-seizing beak, a carrier movable about an axis and supporting said looper so that its loop-seizing beak is at one side of said axis, means for actuating said carrier, and a thread-controller for said looper-thread including spaced thread-guides, and a thread-eye provided in said looper on that side of the carrier-axis remote from the looper-beak.

20 10. A sewing machine having in combination, a reciprocating thread-carrying needle, a threaded chain-stitch looper having a loop-seizing beak and a supporting shank, a carrier movable about an axis, means for securing said looper-shank to said carrier, and a thread-controller for said looper-thread including spaced fixed thread-guides, and a thread-eye formed in said looper-shank and operable on the thread between said thread-guides.

25 11. In a chain-stitch sewing machine, in combination, a reciprocating thread-carrying needle, a thread-carrying looper complementary to said needle in the formation of stitches, means including a pair of spaced thread guides for directing the looper-thread to said looper, a looper-thread controller in engagement with the portion of the looper thread extending from one to the other of said thread-guides, and actuating means operatively connected for rocking said controller about an axis having an orbital path of movement.
